UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

DESIGN FOR A FEED-THROUGH SWITCH.

50,353.

Specification for Design.

Patented Feb. 20, 1917.

Application filed November 8, 1916. Serial No. 130,277. Term of patent 14 years.

To all whom it may concern:

Be it known that I, CHARLES J. KLEIN, a citizen of the United States, residing at Milwaukee, in the county of Milwaukee and State of Wisconsin, have invented a new, original, and ornamental Design for Feed-Through Switches, of which the following is a specification, reference being had to the accompanying drawing, forming part thereof.

Figure 1 is a front elevation view of a feed through switch showing my new design. Fig. 2 is a side elevation view thereof.

I claim:

The ornamental design for a feed through switch, as shown.

CHARLES J. KLEIN.
